UNITED STATES PATENT OFFICE

2,415,227

VEGETABLE TOPPER

William E. Tenbrook, Glenwood Springs, Colo.

Application August 4, 1943, Serial No. 497,358

5 Claims. (Cl. 146—81)

1

This invention relates generally to cutting devices and pertains particularly to a cutter designed for use in grocery stores and vegetable markets for cutting vegetables and more particularly for cutting off or removing vegetable tops.

The present invention constitutes an improvement upon my prior Patent No. 2,322,905.

In grocery stores and vegetable markets generally, the majority of customers desire to have the tops of such vegetables as beets, turnips, carrots, onions and the like removed before taking the same and the present practice in a majority of stores is to twist off the tops with the result that the grocer's hands become messy and the general results are anything but satisfactory. The present invention has for its object to provide a very simple type of device by means of which such tops can be easily and quickly cut off from the body of the vegetables.

Another object of the invention is to provide a vegetable top cutter having an oscillating knife, wherein a novel means is provided for effecting the oscillation of the knife and at the same time for protecting the user against injury.

A still further object of the invention is to provide a vegetable top cutting device having an oscillating knife and an oscillating knife guard, with means for swinging or oscillating the guard to effect the movement of the knife, the guard acting to receive the knife as the latter moves, so that the operator will not be subjected or exposed to the danger of having the knife strike his hand during the cutting operation.

Still another object of the invention is to provide a vegetable top cutting device of the character stated, in which the oscillating knife and guard are operatively coupled by a novel linkage to effect the movement of the knife into the guard, as above stated, and in which a means is provided for returning the knife and guard to their initial or starting positions wherein they coact to form a receiver in which the vegetable tops are placed prior to being cut.

The invention will be best understood from a consideration of the following detailed description taken in connection with the accompanying drawing, with the understanding that the invention is not limited by the showing of the drawing but may be changed or modified within the scope of the appended claims.

In the drawing:

Figure 1 is a side elevational view of my device with a cutting blade and a parallel side portions 7 in position to receive the material to be cut.

2

Figure 2 is an end elevational view taken at right angles to the device as shown in Figure 1.

Figure 3 is a cross-sectional view taken along the line 3—3 of Figure 1.

Referring now more particularly to the drawing, the numeral 1 designates a plate or body which may be mounted upon a wall or in any other suitable manner and upon which is secured the several parts of the cutter device.

Attached to the face of the body 1 is a plate 2 having a longitudinal forwardly extending flange 3. This plate is secured vertically as illustrated.

Pivotedly attached, as at 4, to the flange 3 adjacent its lower end is the free end of the inwardly curved lower portion 5 of a knife guard indicated generally by the numeral 6. This guard is made to have the two spaced parallel side portions 7 connected together at their upper ends, as indicated at 8, and shaped at their lower ends to form the inwardly curved portions 5 previously referred to, and the free ends of these inwardly curved portions may be attached to the flange 3 by having the flange interposed between them, so that the pivot member 4 will pass through the two portions and the flange, as is clearly shown in Figure 3.

As shown, the major portion of the length of the guard 6 is straight and the guard normally extends outwardly and upwardly with respect to the flange 3 to which it is attached, the upper end of the guard being spaced a substantial distance from the flange to receive the vegetable tops. The upper end portion of the guard may be supplied with a handle 9 or other suitable means to facilitate grasping the guard and oscillating it forwardly and downwardly when necessary.

At a suitable point above the pivot 4 of the guard is a link pivot 10 which parallels the pivot 4 and to which is attached one or a pair of links 11. A pair of such links is here illustrated and these extend downwardly in parallel relation across the curved lower portion 5 of the guard and are connected at their outer or free ends by a pivot 12.

The numeral 13 generally designates a knife which has a shank portion 14 which is disposed between the curved lower end portions 5 of the two side parts 7 of the guard. At the inner end of the shank a pivot pin extends through the two portions of the guard and through the knife, as indicated at 15, while the lower or free end of the shank 14, which is located between the lower ends of the links 11, is attached to the pivot 12.

The portion of the knife adjacent the shank through which the pivot pin 15 passes is provided with a slot 16 to allow for turning and longitudinal movement of the knife as the guard is pulled outwardly away from the flange 3. It will be readily seen that with the arrangement illustrated and described, when the guard 6 is pulled outwardly and downwardly, an outward and downward pull will be applied to the shank end of the knife and cause the knife to oscillate on the pivot 12 so that the cutting edge 17 thereof, which faces outwardly, will move toward the guard and into the space between the side portions of the guard.

The normal or inoperative position of the guard 6 is substantially upright, as shown in Figure 1, and the normal or inoperative position of the knife is extending upwardly and inwardly from the lower part of the guard toward the body 1. There is thus provided a substantially V-shaped space into which the heads or tops of the vegetables can be placed.

These parts are maintained, when the machine is not in use, in the normal or inoperative positions described, by a spring 18 which has one end fixed to the flange 3 or in any other suitable manner, at a substantial point above the pivot 10, while the other end of the spring is attached to the guard or to the pivot at 15. Thus, when the guard is oscillated outwardly and downwardly, the spring will be placed under tension at the same time that the knife is performing the desired cutting operation and when the guard is released, the spring will return the parts to their original positions in readiness for the introduction of another bunch of tops or other articles to be cut.

From the foregoing it will be readily apparent that in the device herein disclosed the operator is not required to touch the knife at all and consequently the danger of being cut in moving the knife is materially reduced. Also the knife as it moves forward has its cutting edge covered so that there is no danger of the operator putting his hand against such edge or bringing any part of his body in contact therewith.

If desired, in order to further insure the stopping of the knife after the cutting edge has entered the guard, the upper portion of the guard may be provided with a cross-stop 19 which will extend across the edge of the knife after it has entered the guard and thus prevent the knife edge from passing entirely through the guard.

What is claimed is:

1. A vegetable topper of the character described, comprising a relatively long knife and a relatively long knife actuating member having a crossed relation adjacent to one end, a sliding pivot coupling between the knife and actuating member at the crossed portions thereof whereby the knife and member have relative scissor-like movement, a support, means pivotally connecting the actuating member, at the end adjacent to its pivotal connection with the knife, with the support, and a link extending across the actuating member between the pivot coupling and the said pivotal connection and positioned between the knife, adjacent to its pivoted end, and said pivotal connection and pivotally coupled between the knife and the support and functioning to effect the swinging of the knife away from the support.

and toward the member when the member is swung away from the support.

2. A vegetable topping device of the character stated, comprising a support adapted to be vertically mounted, an elongated guard member having a curved lower end portion pivotally attached to the support whereby the major extent of the guard member extends upwardly and outwardly with relation to the support, an elongated knife having a shank, a sliding pivotal connection between the knife at the shank end and the elongated member adjacent its curved end, whereby the knife and elongated member normally form a V, and a link connection between the knife shank and said support at a point above the pivot for the elongated member.

3. A structure as set forth in claim 2, in which said elongated member comprises two spaced parallel portions between which the pivoted end of the knife extends, whereby the elongated member forms a guard to receive the cutting edge of the knife, and means carried by the elongated member for facilitating its oscillation.

4. A structure as set forth in claim 2, including a spring connection between the lower part of the elongated member and the support therefor, whereby the elongated member is constantly urged to swing upwardly and inwardly toward the support.

5. A vegetable topping device comprising a support, a relatively long member pivotally attached at one end to the support, a relatively long knife having a longitudinally extending shank at one end and having the shank end in crossed relation with said member adjacent to the pivoted end of the member, said knife having an obliquely directed slot therein in the part thereof which lies across the member, a pin carried by said member and engaging in said slot, a link extending across the member between the pivoted end of the member and said pin, a pivotal connection between an end of the link and the support, and a pivotal connection between the other end of the link and the knife shank upon the side of said member remote from the end of the link which is pivoted to the support, the axes of the said pivotal connections for the ends of the link and the pivotal connections between the member and the support being substantially parallel, and said support comprising an actuating means for the knife and functioning when swung away from the support to effect the swinging of the knife away from the support and into cutting relation with the said member.
